US0D1084822S

(12) **United States Design Patent** (10) **Patent No.:** **US D1,084,822 S**
(45) **Date of Patent:** **** Jul. 22, 2025**

(54) **KEY IDENTIFIER**

- (71) Applicant: **Nite Ize, Inc.**, Boulder, CO (US)
(72) Inventor: **Gregory M. Adelman**, Boulder, CO (US)
(73) Assignee: **NITE IZE, INC.**, Boulder, CO (US)
(**) Term: **15 Years**

(21) Appl. No.: **29/876,969**

(22) Filed: **May 31, 2023**

(51) **LOC (15) Cl.** **08-07**
(52) **U.S. Cl.**
USPC **D8/347**

(58) **Field of Classification Search**

USPC D8/323-329, 356-359, 333-334,

(57) **CLAIM**

The ornamental design for a key identifier as shown and described.

DESCRIPTION

FIG. 1 is a front, upper perspective view of a key identifier showing the new design;

FIG. 2 is a front, lower perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines in the drawings are included for the purpose of illustrating portions of the key identifier that form no part of the claimed design.

1 Claim, 8 Drawing Sheets
